SPINNING BUCKET

Horace Pugh Fry, Jr., Swarthmore, Pa., assignor
to American Viscose Corporation, Wilmington,
Del., a corporation of Delaware

Application March 20, 1942, Serial No. 435,462

9 Claims. (Cl. 57—76)

This invention relates to improved cover-locking means for spinning buckets such as are used in collecting artificial filamentary material. It is particularly concerned with a novel form of cover-locking means adapted to automatically lock by virtue of centrifugal force upon rotation of the bucket and to be readily released by the fingers of an operator when he removes the cover from the box or equally as readily by a cake-removing device adapted to be inserted into the box when a form of box is employed which permits the removal of the cake therefrom by means of such a device.

In the drawing, illustrative of the invention, Figure 1 is an elevational view in cross-section of the combination of a spinning bucket with the cover-locking means and a device adapted to remove the cake therefrom.

Figure 2 is a plan view of the cover with its locking means, and

Figure 3 is a view showing a locking element enlarged.

Figure 4 is a vertical cross-section of a spinning bucket inverted upon a cover releasing form, and

Figure 5 is a plan view of the cover releasing form.

The spinning bucket 2 is provided with a groove 3 in its upper internal periphery which is adapted to cooperate with the bucket-engaging members 4 provided within the cover 5. These members 4 are shown in detail in Figure 3 and each comprises an elongated finger-like body portion having a longitudinal slot 6 therein. The body portion terminates in the bucket-engaging tip 7 shaped to conform with the groove of the bucket. The other end of the elongated body portion is provided with the upstanding portion 8 which is provided with a sloped surface 9 down to the body portion. These finger-like members are mounted slidably within radially extending slots 10 of rectangular cross-section within the cover and the overall length of these members preferably corresponds to the difference between the inner and outer radii of the annular cover which may be provided at its inner periphery with an upstanding annular portion 11. A pin 10a may be provided in the cover to cooperate with each slot 6 to limit its slidable motion. The annular portion 11 as well as the upper face of the cover is cut away suitably as at 12 to permit a certain amount of radial motion of the finger-like member 4 with its upright end portion 8. This is preferably done in a manner to minimize air resistances and, as shown in Figures 1 and 2, an annular groove 13 may be provided in the top

surface of the cover which extends down to the recesses 10 within which the finger-like members are set. Upon rotation of the spinning bucket after the cover has been put in place, these finger-like members 4 are thrown outwardly into engagement with the groove 3 provided within the internal periphery of the bucket, thereby locking the cover in place during the collecting operation. After the cake has been collected and it is desired to doff, it is merely necessary for the operator to place his fingers upon the several sloped surfaces 9 of the finger-like members 4 and press them inwardly, at the same time grasping the upstanding annular ring 11 upon the cover for simultaneous unlocking and removal by hand of the cover.

The operation just described refers to the simple manual removal of the cover which may be followed by the removal of the cake by any suitable means, such as the inversion of the bucket and removal by gravity with manual assistance. However, it is also within the contemplation of this invention to provide the spinning box with a removable element 14 for supporting the cake within the bucket and to remove the cake with this supporting element by means of a device 15 which is adapted to release the cover-locking means upon insertion into the bucket.

Any suitable form of cake-supporting element 14 and cake-removing device 15 may be employed. Figure 1 shows one preferred embodiment formed of a cylindrical member 16 having a diameter adapting the member to slidably fit within the internal periphery of the cover 5 and provided at its lower end with an inwardly flared portion 17 adapted for firm seating engagement with the complementarily shaped internal periphery of the cake-supporting element 14 and with the spring element 18 having hook-like portions 19 adapted to permit insertion of the lower end of the device into the internal periphery of the removable element 14 and to thereupon spring outwardly into the undercut portions 20 of the removable element and clamp it into firm seating engagement with the flared portion 17 of the device. The upper end of the device is provided with a flared portion 21 across which a handle in the form of a tube or rod 22 extends. The device is also provided at the upper end of the cylindrical member with an annular concentric depending sleeve 23 which engages the sloped surfaces 9 upon the finger-like members as the cake-removing device seats itself upon the cake-supporting element 14 within the box, in this fashion disengaging the cover from the spinning

box so that the entire contents may be removed as an integral unit.

Instead of releasing the cover by hand and inverting the bucket or removing the cake with the cover by a tool as in Figure 1, the cover may be released by inversion upon a form for this purpose which may be mounted upon a platform or cake conveyor. This releasing form as shown in Figures 4 and 5 comprises two upright guides 24 and 25 and a vertical tubular member 26 concentric therewith. The tubular member is adapted to encircle the upstanding annular portion 11 of the cover and to force the members 4 inwardly by contact with their sloped surfaces 8 when a cake-filled bucket is inverted and deposited on the form while being directed by the guides 24 and 25. Upon lifting the bucket, the cake is left upon its cover and may be readily grasped without seriously damaging it to remove it to any desired point of operation.

While preferred embodiments of the invention have been shown, it is to be understood that changes and variations may be made without departing from the spirit or scope of the invention as defined by the appended claims.

I claim:

1. A spinning bucket cover having a plurality of radially slidable cover-locking members arranged to be thrown centrifugally into engagement with a spinning bucket upon rotation therewith, said members having bucket engaging portions at their outer ends and upwardly and inwardly sloped portions arranged at their inner ends and adapted to be embraced and to be moved inwardly by a common encircling device whereby release of said cover-locking means from said bucket is effected.

2. A spinning bucket cover releasing device comprising a tubular member and means associated therewith for guiding a spinning bucket concentrically with respect thereto.

3. A spinning bucket cover releasing device comprising an upright tubular member and means arranged outside said member presenting a guideway extending in a direction parallel to the axis of said member.

4. A spinning bucket cover releasing device comprising an upright tubular member and guide means arranged concentrically about said member for guiding a spinning bucket having a cover locked therein into concentric axial relationship with the tubular member to release the cover.

5. An annular spinning bucket cover having an annular hand grip member adjacent its internal periphery, means in said cover arranged to be thrown centrifugally into engagement with a

spinning bucket upon rotation therewith and having sloped portions normally retracted within said member but movable outwardly with respect thereto upon movement of said means into bucket engaging position.

6. An annular spinning bucket cover having a plurality of cover-locking members recessed therein radially movable inwardly to retracted position and outwardly into bucket engaging position, said members having inner portions having outward-facing sloped surfaces and an annular groove in the upper surface of said cover surrounding the sloped portions of said members for accommodating a device for embracing and retracting the sloped portions and thereby said members.

7. A spinning bucket having an annular cover, upstanding means on said cover affording manual gripping thereof, cover-locking means on said cover arranged to be thrown centrifugally into engagement with said bucket, said cover-locking means being provided with manual releasing means arranged in proximity to said manual gripping means for substantially simultaneous manipulation therewith.

8. A spinning bucket having a cover, an upwardly extending annular hand grip member adjacent its internal periphery, at least one radially movable cover-locking element having an outer bucket-engaging portion and an inner portion provided with an inwardly and upwardly sloped surface facing outwardly, said element being arranged to be thrown centrifugally with its outer portion into bucket-engaging position and with its sloped surface to a position externally adjacent to said hand grip member whereby substantially simultaneous manipulation of said element by its sloped surface portion to release the cover from the bucket and manual gripping of said cover by said hand grip member may be effected.

9. In combination, a spinning bucket having a cover and a removable cake-supporting member, cover-locking means on said cover comprising at least one element arranged to be thrown centrifugally into engagement with said bucket, said element having an outer bucket-engaging portion and an inner portion provided with an inwardly and upwardly sloped surface facing outwardly, and a device insertible into said bucket through said cover for gripping said cake-supporting member and having a concentric downwardly extending sleeve adapted to encircle the sloped surface and to move said elements inwardly as said device is inserted in said bucket.
